JOSEPH A. FIRSCHING, OF UTICA, NEW YORK

KNITTED FABRIC AND METHOD OF PRODUCING THE SAME

Application filed November 15, 1921. Serial No. 515,203.

This invention relates to a new and improved knitted fabric and the method of producing the same.

The main object of the invention is the production of a novel and attractive fabric. Other objects and advantages relate to the details of the method whereby the fabric is produced, and to the specific details of the structure of the fabric, all as will more fully appear from the following description, taken in connection with the accompanying drawings, in which:—

Figure 1 is a top plan view of a portion of a knitting machine for accomplishing the invention.

Figure 2 is a view partly in section of the stitch wheel and one of the needles.

Figure 3 illustrates the thread as applied to the needles by the stitch wheels illustrated.

Figure 4 is a view similar to Figure 2 illustrating the beard of the needle as closed by the plugged stitch wheel.

Figure 5 is an illustration of one of the plugs used for closing the beard.

Figure 6 illustrates the mechanism designed for setting the patterns.

Figure 7 is a view of this mechanism at right angles to Figure 6.

Figure 8 is an illustration somewhat enlarged of the appearance of the threads when unraveled from a particular fabric of my invention.

Figure 9 is a greatly enlarged view of a section of fabric.

The apparatus used in accomplishing the invention is in the nature of a combination of the standard knitting machine having circularly arranged needles and of other special mechanism, and in Figure 1 such mechanism

is shown as applied to such a machine embodying needles —1— of a usual and ordinary construction, said needles embodying a flexible resilient beard —20— under which the thread is placed for the formation of knitted loops in the usual manner. The thread is placed under the beards —20— of the needles by means of stitch wheels 2, 3 and 4 respectively illustrated in Figure 1. Each stitch wheel in the ordinary knitting machine is designed for placing its particu-

lar thread under the beard of each needle for the formation of a knitted loop upon each needle when the cloth is moved from the depressed portion in which it is held by the shoe or plate, and the last formed knitted loops will be near the bottom of the needle, such last formed knitted loops being cast off after the thread has been placed underneath the beard of the needle, all in the usual manner.

For the purpose of illustrating one form of my invention which at present is deemed satisfactory for the production of a novel and attractive cloth, I have shown three stitch wheels —2—, —3— and —4—, one of which, as the wheel —2— is adapted to place a thread under the beard —20— of every other needle.

In other words, the stitch wheel —2— places its thread under the beard —20— of one needle, skips the next needle, then places its thread under the beard of the succeeding needle thereby forming two knitted loops separated by a pile loop.

This is effected by placing a plug —7— in the space between certain of the blades of the wheel, and in this particular illustration a plug is placed between alternate pairs of blades of both the wheels —2— and —3—. These plugs —7— are shown in Figures 1 and 5 and may be secured between the blades —8— of an ordinary stitch wheel in any suitable manner, and as illustrated the plug is formed with a laterally extending lug or flange 9 which is adapted to fit in an opening in one of the adjacent blades, and is thereby held in that position when the wheel is assembled in the usual and well known manner.

The plug —7— is of such a form that when the projecting end portions —10— of the stitch wheel bring the thread adjacent the lower end of the beard —20—, the plug —7— moves the end of the beard against the body of the needle and into the usual recess formed therein so that the thread instead of being forced or moved under the beard —20— slips up outside the beard, and a knitted loop is not formed upon that needle by that thread, but the excess thread forms a pile loop upon one side of the resultant fabric.

These plugs, as stated, may be placed in alternate spaces between the blades of the ordinary stitch wheel and the construction of the stitch wheel —3— is the same as that of the stitch wheel —2— so far as its physical formation is concerned.

However, its arrangement with respect to the needles is such that it places a thread under the beard of the needle and thereby forms a knitted loop upon the needle which the stitch wheel —2— skips, and then skips the needle upon which the stitch wheel —2— has placed a knitted loop, or in other words it moves a thread under the beard —20— whereby a knitted loop is formed so that the wheel —3— forms a pile loop where the wheel —2— forms a knitted loop.

In other words, in this particular illustration, two plugged stitch wheels, provided with suitably arranged plugs, are utilized, and the wheel —2— places a knitted loop on one needle and skips the next, and continues that all the way around the needles of the machine, while the wheel —3— places a knitted loop upon the needle which the wheel —2— has skipped, and then skips the next needle and continues that operation all the way around the needles of the machine.

The stitch wheel —4— is not provided with any plugs, but is of the usual form adapted to move the thread under the beard —20— of every needle so that it forms a knitted loop upon every needle.

In other words, the wheel —4— produces with its thread a regular, uniform series of knitted loops and the wheel —2— forms a series of pile loops upon one side of the fabric separated by knitted loops interlocked with alternate knitted loops formed by the wheel —4—, and likewise the wheel —3— forms a series of pile loops separated by knitted loops interlocked with the other alternate knitted loops formed by the wheel —4— so that all of the threads are tied together into and form an inseparable portion of the fabric.

In the usual manner the last knitted loop upon the formed fabric is held at the bottom of the needles —1— during the time that the wheels —2—, —3— and —4— are moving their respective threads underneath the needles or alternate needles, or any other particular selection of needles. When the wheels —2—, —3— and —4— have placed their particular threads in the position and in the sequence desired, either beneath all or a certain portion of the beards upon the needles —1—, the presser plate —12— contacts with the beards upon the needles and moves the ends of the beards into the recesses usually formed in the body of the needles —1—, and at that time the landing wheel —13— moves the knitted loops which are at the bottom of the needles upward over the beards —20—.

A short distance beyond the landing wheel —13— is a cast-off wheel (not shown) of the same or substantially similar construction, which, when the needles move from contact with the presser plate —12— casts off the knitted loop or knitted loops from the needle. The operation continues by the knitted loops thus formed on the needles being moved downwardly to the base of the needles by the shoe or plate —6—, which moves the knitted loop so formed downwardly to the base of the needle and the operation continues in the same manner by the placing of the thread underneath the beard of the particular needles desired by means of the stitch wheels —2—, —3— and —4—, or similar wheels.

As illustrative of this particular embodiment of my invention, the stitch wheel —2— skips the needle —14—, places a thread under the beard of the needle —15—, skips needle —16—, places a thread under the beard of needle —17— and continues in this manner.

The stitch wheel —3— places a thread underneath the needle of beard —14—, skips needle —15—, places a thread under the beard of needle —16—, skips needle —17— and continues in that manner while the stitch wheel —4— places a thread under the beard of each and every one of the needles.

It will be obvious that the wheels —2— and —3— may be provided with plugs in any particular sequence of spaces so as to place a thread under the beard of every other needle, or every third needle or otherwise, as desired, for the formation of a particular fabric.

It is essential, however, that one wheel be used which places a knitted loop on every needle, and this wheel may be in any relative position with respect to the other wheels, that is, it may place a knitted loop under every needle first, or second, or third, or additional wheels may be used, if desired, for the placing of additional threads upon the needles or portion of needles prior to the cast-off of the knitted loop.

It will be noted that in the particular illustration herein used to disclose the invention, each needle contains two knitted loops, while three threads are being continuously supplied to the needles, but it is obvious that that may be varied, and different numbers of knitted loops applied to the different needles to form any desired pattern in a cloth or fabric of the character of my invention.

For the purpose of setting the pattern, i. e. for the purpose of arranging the stitch wheels —2— and —3— so that they will apply knitted loops to the desired needles, in this case, to alternate needles, the wheel —3— applying a knitted loop to the needle that the wheel —2— skips, I have formed the wheels —2— and —3— with dials or marks

of some character, as graduations, which mark —30—, groove or graduation is adapted to be moved into registration with an indicator or pointer —18—, and when brought into registration with said pointer, the pattern is properly set.

When the machine is originally set up, these stitch wheels can be properly set by means of the pointer and the graduation upon the wheel, and should the pattern change or vary in any way, it is only necessary to turn the machine until the graduation upon one of the wheels comes into alignment or registration with its particular pointer, and in an instant the operator can detect which one of the stitch wheels is off, and can immediately place it in line with its particular indicator to set the original pattern.

When a particular cloth of my invention made by the present method herein illustrated and described, is unraveled, the particular three threads which are placed upon the needles by the three wheels —2—, —3— and —4—, will have the appearance shown in Figure 8, the thread —20— being the thread that is placed upon the needles by the wheel —4—, which places the thread beneath the beard of each needle, while the other two threads —21— and —22— are the threads placed upon alternate needles by the wheels —2— and —3—, which alternately form pile loops which extend to one side of the fabric only, and produce the characteristic appearance of the cloth of my invention.

The length of the pile loop extending from one side of the fabric is governed by a longer or shorter knitted loop on the wheel —4— which puts a knitted loop under the beard of every needle, but that adjustment has only a small limit. In order to get any great variation, it is necessary to make larger plugs —7— for shorter pile loops and smaller plugs —7— for larger or longer pile loops. When small plugs are used the plates of the stitch wheel, when closing the beard so that a knitted loop will not be made, will be forced into the needles further than when large plugs are used and consequently more yarn will be used in making the pile loop where the thread is dropped than would be used when a large plug is utilized.

In Figure 9 there is illustrated a small portion of the fabric in which the thread —40— is shown as formed into a regular, uniform series of knitted loops while the thread —21— is formed into a series of pile loops numbered —50—, separated by knitted loops which are interlocked with alternate knitted loops formed by the thread —40—.

In a similar manner, the thread —22— is formed into a series of pile loops 51 interlock with alternate knitted loops formed by the thread —40—, but being different alternate knitted loops than those with which the thread —21— is interlocked, whereby two

series of pile loops are formed which extend to one and the same side of the fabric, both of which are interlocked in the fabric by engagement with alternate knitted loops of the regular uniform series of knitted loops formed by the thread —40—.

It will be obvious to those skilled in the art that by the use of my invention, various patterns of cloth of my invention can be made, that the skip of pile loops and knitted loops may be in any desired sequence in accordance with the desires of the maker, and that any desired number of ends and wheels may be used, and in any alternate or other relation desired, and that various changes, modifications and substitutions may be made in the details of the process, the machine, and the products, without departing from the invention as set forth in the appended claims.

I claim:

1. A knit fabric comprising three threads one of which is formed into a regular series of uniform knitted loops and each of the other two of which is formed into a series of uniform knitted loops of a size substantially the same as the knitted loops of the first named thread, the knitted loops of the two last named threads overlying alternate and different knitted loops of the first named threads, and the knitted loops of each of the two last named threads being separated by pile loops of uniform size extending to one and the same side of the resulting fabric.

2. The method of producing a knit fabric formed of three threads comprising forming one of the threads into a regular series of uniform knitted loops, forming each of the other two threads into a series of uniform knitted loops of substantially the same size as the knitted loops of the first named thread with their knitted loops alternately positioned, interlocking the knitted loops of one of the last named threads with alternate knitted loops of the first named thread, interlocking the knitted loops of the other last named thread with alternate and different loops of the first thread, each of the last two named threads being formed into pile loops of uniform size intermediate the knitted loops and extending to one and the same side of the resulting fabric.

3. The method of knitting comprising forming a uniform regular series of knitted loops, forming a series of knitted pile loops of uniform size, interlocking said knitted pile loops with alternate knitted loops of the first series, forming a second series of knitted pile loops corresponding in size to the first series of knitted loops, and interlocking the second series of knitted pile loops with the remaining knitted loops of the first series.

4. A fabric formed of a plurality of threads in which one thread is formed into a series of knitted loops of regular and uniform size uniformly spaced, and a second

thread formed into a series of knitted pile loops of uniform size extending to one side of the fabric, said last named loops separated by knitted loops interlocked with alternate knitted loops of the first thread, and a third thread formed into a series of knitted pile loops corresponding in size to the knitted pile loops of the second thread and extending to the same side of the fabric, said knitted pile loops of the third thread being separated by knitted loops interlocked with alternate knitted loops of the first thread.

In witness whereof I have hereunto set my hand this 3d day of November, 1921.
